(57) **CLAIM**

The ornamental design for a monitor, as shown and described.

DESCRIPTION

FIG. 1 is a front-top perspective view of a monitor according to the claimed design.

FIG. 2 is a front-bottom perspective view of the monitor.

FIG. 3 is a rear-top perspective view of the monitor.

FIG. 4 is a rear-bottom perspective view of the monitor.

FIG. 5 is a front view of the monitor.

FIG. 6 is a rear view of the monitor.

FIG. 7 is a top view of the monitor.

FIG. 8 is a bottom view of the monitor.

FIG. 9 is a left side view of the monitor.

FIG. 10 is a right side view of the monitor; and,

FIG. 11 is a cross-sectional view of the monitor taken along line 11-11 in FIG. 10.

The dash-dash broken lines in the figures illustrate portions of the monitor that form no part of the claimed design.

The dash-dot-dot broken lines in FIGS. 3-4 and 7-10 depict the boundary of the claimed design, with the claim extending to the boundary and with the boundary itself forming no part of the claimed design.

The long-dash short-dash broken lines in FIG. 10 illustrating the cross-section line form no part of the claimed design.

(Continued)

The dashed hatch shading in FIG. 11 illustrates interior portions of the monitor that form no part of the claimed design, but the exterior surfaces of the same illustrated in solid lines are claimed.

The vent features at the underside of the monitor illustrated in broken lines form no part of the claimed design.
